CLAIM

The ornamental design for a magazine rack, as shown
and described.

DESCRIPTION

FIG. 1 is a front perspective view of a magazine rack
showing my new design;

FIG. 2 is a rear perspective view of the magazine rack
of FIG. 1;

FIG. 3 is a front elevational view of the magazine rack
of FIG. 1; and

FIG. 4 is a front perspective view showing a second
embodiment of the magazine rack shown in FIG. 1.

FIG. 2

FIG. 1

FIG. 4

FIG. 3
